UNITED STATES PATENT OFFICE.

PHILIP D. POLLARD, OF DENISON, TEXAS.

DESIGN FOR A POCKET-CUSPIDOR.

SPECIFICATION forming part of Design No. 31,397, dated August 15, 1899.

Application filed July 24, 1899. Serial No. 725,008. Term of patent 7 years.

To all whom it may concern:

Be it known that I, PHILIP D. POLLARD, a citizen of the United States, residing at Denison, in the county of Grayson and State of Texas, have invented and produced a new and original Design for a Pocket - Cuspidor, of which the following is a specification.

The invention relates to a new and original design for a pocket-cuspidor; and it has for its object to provide a design of this character which will be both useful and ornamental.

The essential feature of the design resides in a cuspidor having a bowl of approximately trunco-conical shape and provided with a tapering sleeve or lining depending from the upper edges of the bowl, said bowl having an approximately straight handle extending from one side of it.

In the drawings, Figure 1 is a perspective view of a pocket-cuspidor, showing my new and original design. Fig. 2 is a plan view of the same. Fig. 3 is a vertical sectional view.

Referring to the drawings, 1 designates a pocket-cuspidor having a tapering bowl 2 of

approximately trunco-conical shape and provided with a tapering inner portion or shell 3, consisting of a sleeve and depending from the upper edges of the bowl. The bottom 4 of the bowl is circular and flat, and the walls of the inner sleeve or lining 3 are inclined in the opposite direction from the walls of the bowl. The cuspidor is provided at one side of the bowl with an approximately straight tubular handle 5, arranged at an inclination. The handle is slightly tapered toward the bowl, and it is provided at its outer end with a cap 6.

What is claimed is—

The design for a pocket-cuspidor herein shown and described.

In testimony that I claim the foregoing as my own I have hereto affixed my signature in the presence of two witnesses.

PHILIP D. POLLARD.
